UNITED STATES PATENT OFFICE

162,495

TWIN BABY STROLLER

Roy Lane Trimble, Bloomington, Ill.

Application March 11, 1949, Serial No. 1,361

Term of patent 7 years

(Cl. D14—14)

To all whom it may concern:

Be it known that I, Roy Lane Trimble, a citizen of the United States, residing at Bloomington, in the county of McLean, State of Illinois, has invented a new, original, and ornamental Design for Twin Baby Stroller, of which the following is a specification, reference being had to the accompanying drawing, forming part thereof.

In the drawing:

Figure 2 is a fragmentary perspective view illustrating the rear portion of the stroller; and

I claim:

The ornamental design for a twin baby stroller, as shown.

ROY LANE TRIMBLE.
